ELECTRIC DECADE RESISTANCE UNIT

Robert J. Couts, Akron, and Charles D. Morrill, Cuyahoga Falls, Ohio, assignors to Goodyear Aircraft Corporation, Akron, Ohio, a corporation of Delaware

Application April 1, 1954, Serial No. 29,802

Term of patent 14 years

(Cl. D26—1)

Figure 1 is a perspective side view of an electric decade resistance unit showing our new design;

Figure 2 is a top perspective view.

Figure 3 is a top plan view; and

Figure 4 is a bottom plan view thereof.

We claim:

The ornamental design for an electric decade resistance unit, as shown.
